United States Patent Office.

STEPHEN P. M. TASKER AND ROBERT BRIGGS, OF PHILADELPHIA,
PENNSYLVANIA.

Letters Patent No. 92,761, dated July 20, 1869.

IMPROVED APPARATUS FOR DRAWING TUBE-SKELPS.

The Schedule referred to in these Letters Patent and making part of the same.

To all whom it may concern:

Be it known that we, STEPHEN P. M. TASKER and ROBERT BRIGGS, both of Philadelphia, in the county of Philadelphia, and State of Pennsylvania, have invented a new and useful Improvement in Tongs, Mandrel, and Dies, for Bending up the Skelps or Strips of Metal Used in Making Tubes; and we do hereby declare that the following is a full, clear, and exact description thereof, reference being had to the annexed drawings, making part of this specification, in which—

Figure 1 is a longitudinal section through the middle of dies and mandrel, showing the tongs in elevation.

Figure 2 is a section at A.

Figure 3 is a section at B.

Figure 4 is a section at C.

The letters indicate similar parts upon all the figures.

To enable others skilled in the art of making tubes to make and use our invention, we will proceed to describe its construction and operation.

The bending-dies D D are formed of such internal shape as gradually and easily to roll up the flat strip of metal (or skelps) S, while it is drawn by the tongs T, through or between the dies; the tongs T being made as thin or narrow as is consistent with the strain upon them, and passing into the dies along a slot, at P P; this construction and method being that patented by Mildred Blakey, No. 70,397, November 5, 1867, upon whose process our invention is an improvement.

In order to bend skelps of lap-welded tubes, it is the most common practice to have a mandrel placed in between the dies, to sustain the skelp, and keep the edges of the laps together. This has been heretofore done by placing a mandrel upon the skelp and permitting it to be dragged in to the dies with it, a process which leaves a part of the end of the tubes, where the tongs take hold, unsupported, and imperfectly lapped, and also demands a workman to handle and cool the mandrel.

By our improvement the mandrel is permanently placed in the dies, being held from passing through by a shoulder or projection at g, and along the top of this mandrel we form a groove or slot, N, in which the lower bit or nose of the tongs can lie.

Furthermore, in order to prevent the drawing of the tongs from depressing the mandrel upon the dies, or cramping the iron of the skelp by an unfair pull with regard to the dies, we have found it expedient to support the nose of the tongs by a carrying-pin, U, which is made to ride upon flanges E E, attached to the dies, the upper edges of which are parallel to the inside of

the top of the die, so that the skelp is sustained whilst the tongs are passing through or along the die or mandrel, after which time, the skelp being lapped smoothly around the mandrel, no further external support is needed.

We are aware that skelps have been bent by means of solid or fixed dies, which give the outer shape to the bent skelp, with and without the combination of a fixed or movable mandrel to give the inside shape to the bent skelp, the whole being used in connection with the ordinary draw-bench and lazy-tongs, where the end of the skelp is previously bent into shape, or is trimmed down to a point, or has a "helper" (or handle) welded or brazed upon it, such end, point, or "helper" being inserted through the die, so as to be grasped by the lazy-tongs. Arrangements and combinations of this kind are of well-known, long-continued, and even ancient use, and are constantly practised, in the manufacture of stair-rods, brass mouldings and tubes, tubular sash-bars, and other hollow or trough-forms; but we do not claim any improvement except in combination with such fixed dies as will admit the tongs to be passed along, and through them, so that the tongs can lay hold upon the unbent and unprepared end of the skelp.

We are aware of the invention of Mildred Blakey, before referred to, and disclaim anything therein claimed or described, this, our invention, being applicable therewith as an improvement; but

What we claim as our invention, and desire to secure by Letters Patent, is—

1. The permanent or fixed mandrel, in combination with two permanent and fixed dies, whose upper edges are separated longitudinally, so that the tongs can be passed along and between them, to lay hold upon the skelp, substantially as described.

2. Also, the slot or groove along the mandrel, in which the lower bit or jaw of the tongs can pass, while the end of the skelp, to which the tongs are attached, is passing the dies, substantially as described.

3. Also, the pin or carrier for supporting the nose or end of the tongs while passing along the dies, substantially as described.

4. Also, the flanges or sliding surfaces F F, formed upon the dies or independent of them, upon which the pin, or its equivalent mechanical device, can be made to move, substantially as described.

STEPHEN P. M. TASKER.
ROBT. BRIGGS.
